APPARATUS FOR TREATING SURFACES

Cort G. Platt, Minneapolis, and Winston E. Sabačka, St. Paul, Minn.

Application May 25, 1950, Serial No. 164,082

10 Claims. (Cl. 51—15)

1

The invention herein presents a novel and improved method of treating surfaces, such, for example, as surfaces of spark plugs to be cleaned, and a new and improved apparatus by employment of which the method can be practiced. A description of the apparatus will suffice to make plain a manner in which the several steps of the method can be performed.

Although the principles of the invention are applicable when surfaces of various types of articles or materials are to be cleaned, or otherwise treated, the apparatus as herein illustrated and described has been devised to be especially useful for the purpose of cleaning spark plugs.

In the accompanying drawings forming a part of this specification,

Fig. 1 is a side elevational view of an apparatus made according to the invention adapted to be employed to the accomplishment of the treatment of spark plugs to cause them to be cleaned;

Fig. 2 is a top plan view of the disclosure of Fig. 1;

Fig. 3 is a vertical transverse sectional view, taken on line 3—3 in Fig. 1;

Fig. 4 is a vertical longitudinal sectional view, taken on line 4—4 in Fig. 2; and

Fig. 5 is a detail sectional view, taken on line 5—5 in Fig. 2.

A frame of the apparatus includes a base 10, constituted as a flat rectilinear slab adapted to be rested upon a support therefor, and spaced uprights, denoted 11 and 12, respectively, upon an end portion of said base and disposed in transverse alinement.

The upright 11 fixedly supports a first tubular element 13, the upright 12 fixedly supports a second tubular element 14, said first and second tubular elements 13 and 14 are in alined relation and meet at a location between and spaced from said uprights at farther distance from the upright 11 than from the upright 12, and each of said first and second tubular elements is cylindrical, as well as hollow. A transverse partition wall 15 separates the interior, meeting ends of the first and second tubular elements 13 and 14, the one from the other.

A housing, situated between the uprights 11 and 12 in spaced relation thereto, consists of a hollow cylindrical member 16, in spaced, concentric relation to the first and second tubular elements 13 and 14, as well as in spaced relation to the base 10, comprising an exterior bounding wall of said housing, and closure walls, represented 17 and 18, respectively, upon the opposite ends of said hollow cylindrical member 16, ro-

2

tatably supported, as at 19 and 20, upon said first and second tubular elements 13 and 14 in perpendicular relation thereto and against the possibility of longitudinal movement thereon.

The closure walls 17 and 18 are secured to the opposite ends of the hollow cylindrical member 16 and mounted upon the tubular elements 13 and 14, respectively, in fluid-tight manner. An opening 21 in the closure wall 18, for affording access to the interior of the housing, is covered, also in fluid-tight manner, by a removable closure member 22.

The first tubular element 13 fixedly supports spaced parallel rows of nozzles 23 in spaced, alined relation circumferentially of said first tubular element and disposed within the housing, at the side of the transverse partition wall 15 adjacent the upright 11, which extend upwardly from said first tubular element and terminate in spaced, adjacent relation to the internal surface of the hollow cylindrical member 16 of said housing. As disclosed, the rows of nozzles 23 are spaced equidistantly from each other and from the closure walls 17 and 18, respectively.

Said hollow cylindrical member 16 is shaped to provide a trough 24, disposed exteriorly of the remainder of the hollow cylindrical member and situated adjacent the closure wall 18, between this mentioned closure wall and the transverse partition wall 15. The second tubular element 14 fixedly supports a conveyor tube 25 also disposed within the housing, at the side of said transverse partition wall 15 adjacent the upright 12, which extends vertically downward from said second tubular element and terminates within the trough 24 in spaced, adjacent relation to the transverse center of the internal surface of its bounding wall, constituted as a part of the hollow cylindrical member 16.

The first tubular element 13 opens to the interior ends of the nozzles 23, the exterior ends of said nozzles open to the interior of the housing which in turn is open to the exterior end of the conveyor tube 25, and the interior end of said conveyor tube opens to the second tubular element 14.

An electric motor 26, suitably and conveniently supported upon the base 10 of the frame of the apparatus, is for the purpose of actuating a pump 27, also supported upon said base of the frame, and of causing the housing to be rotated upon the first and second tubular elements 13 and 14. An end portion 28 of the motor shaft 55 adjacent the pump 27 is connected to a drive

shaft 29 of said pump through the medium of a flexible coupling 30, and an end portion 31 of said motor shaft, at the side or end of the motor opposite the pump, fixedly supports a small pulley 32 drivingly connected with the housing through the instrumentality of a belt 33 riding said small pulley and also riding a large pulley 34 fixedly secured to the outer surface of the closure wall 17 in surrounding, concentric relation to the first tubular element 13.

A first pipe connection 35 leads from the pump 27 to a second pipe connection 36 which in turn communicates with an outer end of the first tubular element 13, and a third pipe connection 37 extends between an outer end of the second tubular element 14 and said pump 27. The second pipe connection 36 includes a manually actuatable valve 38 adapted to be closed to preclude passage of fluid through said second pipe connection and open to permit passage of fluid, and the second pipe connection suitably and conveniently supports a heater 39, of ordinary or preferred construction, for warming fluid upon its passage through said second pipe connection.

First, second, third and fourth inlet pipe connections, denoted 40, 41, 42 and 43, respectively, lead to the first tubular element 13 independently of the second pipe connection 36, and manually actuatable valves in said mentioned inlet pipe connections, for precluding or permitting flow of fluid, are indicated 44, 45, 46 and 47, respectively.

An outlet pipe connection 48 leads from the location of jointure of the first and second pipe connections 35 and 36, and said outlet pipe connection is controlled by a manually actuatable valve 49.

The housing is adapted to contain fluid during practical operation of the apparatus, and the fluid can be transmitted to the interior of said housing through any one, or several, of the inlet pipe connections 40, 41, 42, 43. The valves 38 and 49 will be closed while fluid is being conveyed to the housing, as will the valves in the inlet pipe connections other than those open for transmission of fluid.

After fluid is admitted to the housing, the valves which were opened to allow passage of the fluid will be closed and the valve 38 in the second pipe connection 36 will be opened before the electric motor 26 is set in operation to actuate the pump 27. Stated otherwise, the valve 38 will be open and all of the other valves will be closed at all times while said motor and pump are operative to force flow of fluid through the housing.

The outlet pipe connection 48 is for removal of spent fluid from the housing, and when spent fluid is to be removed, the valve 49 will be opened and all of the other valves, including the valve 38, will be closed.

The construction and arrangement will be such that operation of the electric motor 26 while the valve 38 is open and all of the other valves are closed, will cause the pump 27 to be actuated to force fluid into the housing by way of the first and second pipe connections 35 and 36, the first tubular element 13 and the nozzles 23 and withdraw fluid from said housing and return it to said pump by way of the conveyor tube 25, the second tubular element 14 and the third pipe connection 37, and also such that operation of said electric motor while the valve 49 is open and all of the other valves are closed, will cause the pump to be actuated to withdraw fluid from the housing by way of said conveyor tube 25 and said third pipe connection 37 and force the fluid 75

to the outlet pipe connection 48 by way of said first pipe connection 35.

Speaking generally, the housing will contain fluid up to a level below the elevation of the exterior, upper ends of the nozzles 23, and articles or materials the surfaces of which are to be cleaned, or otherwise treated, will be rigidly supported in fluid-tight manner in the hollow cylindrical element 16 with said surfaces exposed at 10 the interior of said housing in vertical alignment with said nozzles 23. During operation of the apparatus, jets of fluid will be continuously forcibly sprayed radially from the nozzles, and the surfaces of each article or material to be cleaned, or otherwise treated, will be alternately subjected to the jets or fluid, while aligned with said jets, and doused into and wiped through the cleaning or treating fluid, naturally retained in the bottom of the housing by reason of gravity. Stated differently, each surface to be cleaned, or otherwise treated, will rotate with the housing to alternately travel through the body of fluid and be subjected to the jets of fluid between intervals when said surface is above said body of fluid 25 and below said jets of fluid in clearing relation to both.

In the disclosure as made, the hollow cylindrical member 16 fixedly supports two spaced rows of spark plugs 50 in parallel planes and in vertical alignment with the nozzles 23, the spark plugs of each row being circumferentially spaced about said hollow cylindrical member.

Each spark plug is removably supported in fluid-tight manner in an annular fitting 51 itself rigidly seated in fluid-tight manner, as at 52, in the hollow cylindrical member 16. An interior portion of each annular fitting 51 includes an internal annular flange 53 with threaded opening 54 for detachably receiving the threaded end 40 portion 55 of a spark plug, adjacent its points 56, and said points are disposed interiorly of the housing to be subjected to the jets of fluid in one or the other of the rows of jets. An intermediate portion of each annular fitting 51 includes an internal annular shelf 57, in spaced relation to the threaded end portion 55 and to an annular shoulder or surface 58 of the spark plug, above said threaded end portion in Fig. 5 of the drawings, and an annular gasket 59 rests upon said annular shelf 57 beneath said annular shoulder or surface. Each spark plug will be made to have a fluid-tight fit merely by turning the threaded end portion 55 into the threaded opening 54 of the corresponding annular fitting to force the annular shoulder or surface 58 of the spark plug down against the corresponding annular gasket 59 thus to cause said annular gasket to be sealingly clamped between said annular shoulder or surface and the annular shelf 57. Openings 60 in 55 each annular fitting 51, at the interior side of the annular shelf 57, permit access of fluid to the adjacent end portion of a spark plug when in the fitting. It will be apparent that spark plugs can be readily and easily removed from the fittings 60 by reversal of the turning movement applied to 65 insert them.

The inlet pipe connections 40, 41, 42 and 43 are of course for the conveyance of different types of fluids, as may be selected, to the housing.

The new and improved method and apparatus are being successfully employed to clean spark plugs of aircraft engines. The fluid being utilized is a strong caustic cleaning compound in liquid condition. The time consumed to the accomplishment of thorough cleaning is anywhere from

one to five hours, depending upon the condition of the surfaces of spark plugs when subjected to the treatment. The openings in the ignition ends of the spark plugs are filled with the cleaning solution when at the lower portion of the housing during its rotation, and cleaning fluid pours out of said openings upon rotation of the spark plugs to the upper portion of said housing. The jets of liquid strike the ignition ends of the spark plugs while clear of the body of liquid in the housing. Alternate immersion and spraying of the surfaces to be cleaned of the spark plugs is accomplished by reason of repeated revolutions of said housing, and successive immersions produce intermittent circulation of the cleaning fluid in and through the spark plug openings. That is, alternate covering or filling and uncovering or draining of the surfaces being treated is accomplished in response to rotation of the housing, and the jets of liquid strike the surfaces while clear of the body of liquid to perform a scrubbing action thereon. Finely divided solid substances can be added to the cleaning compound to act as an abrasive.

The fluid employed can be gaseous or vaporous, as well as liquid. By way of example, compressed air is a gaseous fluid and steam is a vaporous fluid capable of utilization in the apparatus to be operative upon surfaces to be cleaned, or otherwise treated, and, of course, water can be employed, as, for instance, after the cleaning compound has accomplished its purpose, to rinse the cleansed surfaces. And, too, finely divided solid substances can be utilized in the apparatus in dry or moist state to produce abrasive action upon surfaces to be cleaned or otherwise treated.

A typical cycle for cleaning spark plugs is, or could be, as follows:

Treatment of the spark plug surfaces with cleaning fluid, heated or not heated and/or including or not including finely divided substances for accomplishing abrasive action, as may be desirable, until said surfaces are clean; rinsing of the surfaces with water to clear them of loose particles; application of steam to said surfaces to cause them to be heated; and subjection of the surfaces to the action of compressed air to cause them to be dried. By way of example, the first inlet pipe connection 40 can be employed to transmit cleaning fluid to the interior of the housing; the second inlet pipe connection 41 can be utilized to convey water into said housing; steam can be made to enter the housing by way of the third inlet pipe connection 42; and compressed air can be conveyed into said housing through the fourth inlet pipe connection 43. No matter whether the content of the housing, at one time or another, be liquid, vapor, gas or finely divided solid particles in dry or moist state, the pump 27 will be constructed to be capable of causing the content to flow through said housing, out of said pump by way of the first pipe connection 35 and back to the pump by way of the third pipe connection 37, and also capable of removing the content from the housing, by way of the conveyor tube 25 and said third pipe connection 37 to the pump and by way of said first pipe connection 35 to the outlet pipe connection 48.

What is claimed is:

1. An apparatus for treating a surface with a liquid intended to be operative thereon, comprising a housing, a substantially horizontal axis for said housing constituted as first and second tubular elements, said housing including a hollow member in spaced relation to said

first and second tubular elements, means for retaining said surface at a location inside said housing adjacent said hollow member, means for rotating the housing and its hollow member upon the first and second tubular elements to cause said surface retaining means to travel in a circular path substantially in a vertical plane, a nozzle in said housing having fixed relation to and communicating with said first tubular element and including an outlet situated to direct treating fluid against the surface when assembled with said retaining means and rotated with said hollow member, a conveyor tube open at its opposite ends to a lower portion of said housing and said second tubular element, respectively, and means for circulating treating liquid through the first tubular element, said nozzle, the housing, said conveyor tube and the second tubular element while a lower portion of said housing contains a body of the treating liquid in contiguous relation to the hollow member and at elevation below the outlet from said nozzle.

2. The combination as specified in claim 1, and an annular trough provided by said hollow member and disposed exteriorly of the remainder of said housing in which an end portion of said conveyor tube spaced from said second tubular element is situated in spaced relation to the hollow member.

3. In an apparatus of the character described, a housing, an axis for said housing constituted as first and second tubular elements, means for rotating the housing upon said first and second tubular elements, a nozzle in said housing having fixed relation to and communicating with said first tubular element and open to an upper portion of said housing, a conveyor tube open at its opposite ends to a lower portion of said housing and said second tubular element, respectively, and means for circulating a liquid through the first tubular element, said nozzle, the housing, said conveyor tube and the second tubular element while a lower portion of said housing contains a body of said liquid at elevation below the outlet from said nozzle.

4. The combination as specified in claim 3 wherein said housing includes a hollow member in spaced relation to said first and second tubular elements providing an annular trough disposed exteriorly of the remainder of said housing and an end portion of said conveyor tube spaced from the second tubular element is situated in said annular trough in spaced relation to its bounding wall.

5. In an apparatus of the character described, a housing, an axle for said housing constituted as first and second tubular elements, means for rotating the housing upon said first and second tubular elements, said first tubular element being open to an upper portion of said housing, a conveyor tube open at its opposite ends to a lower portion of said housing and said second tubular element, respectively, a pump, first and second pipe connections between said pump and said first tubular element, a first manually actuatable valve in said second pipe connection, a third pipe connection between said second tubular element and the pump, an outlet pipe connection from said first pipe connection, a second manually actuatable valve in said outlet pipe connection, and a motor adapted to be driven while said second manually actuatable valve is closed and said first manually actuatable valve is

open to cause said pump to be actuated to force liquid into said housing by way of said first and second pipe connections and said first tubular element and withdraw fluid from the housing and return it to the pump by way of said conveyor tube, said second tubular element and said third pipe connection, and while said first manually actuatable valve is closed and said second manually actuatable valve is open to cause the pump to be actuated to withdraw fluid from the housing by way of said conveyor tube, said second tubular element and said third pipe connection and force the fluid to said outlet pipe connection by way of said first pipe connection.

6. In an apparatus of the character described, a fitting comprising a hollow body, an internal flange upon said hollow body having a threaded opening for receiving a threaded end portion of a spark plug provided with an annular shoulder in perpendicular relation to said threaded end portion, an internal annular shelf upon said hollow body, and an annular gasket upon a surface of the internal annular shelf opposite said internal flange adapted to be sealingly clamped between said annular shoulder and internal annular shelf in response to turning of said threaded end portion into said threaded opening.

7. An apparatus for treating points of a spark plug with a substance intended to be operative thereon, comprising a housing including a hollow member, means for supporting said spark plug in said hollow member with said points inside said housing adjacent the hollow member and sealing off said hollow member against passage of said substance out of said housing, a nozzle within said housing including an outlet situated to direct said substance radially outwardly of said housing and against said points, means for accomplishing relative rotation of said nozzle and said hollow member with spark plug, and means for forcibly circulating said substance through said nozzle.

8. An apparatus for treating points of a spark plug with a liquid intended to be operative thereon, comprising a housing including a hollow member, means for supporting said spark plug in said hollow member with said points inside said housing adjacent the hollow member and sealing off said hollow member against passage of said liquid from said housing, a nozzle within said housing including an outlet situated to direct said liquid radially outwardly of said housing and against said points, means for rotating the housing and hollow member to cause said spark plug and its points to travel in a circular

path substantially in a vertical plane, and means for circulating said liquid under pressure through the housing by way of said nozzle while a lower portion of said housing contains a body of liquid in contiguous relation to the hollow member and at elevation below the outlet from said nozzle.

9. An apparatus for treating a surface with a liquid intended to be operative thereon, comprising a housing, first and second tubular elements, said housing including a hollow member in spaced, surrounding relation to said first and second tubular elements, means for retaining said surface at a location inside said housing adjacent said hollow member, means for rotating the housing and its hollow member relative to the first and second tubular elements to cause said surface retaining means to travel in a circular path substantially in a vertical plane, a nozzle in said housing communicating with said first tubular element and including an outlet situated to direct treating fluid against the surface when assembled with said retaining means and rotated with said hollow member, a conveyor tube open at its opposite ends to a portion of said housing and said second tubular element, respectively, and means for circulating treating liquid through the first tubular element, said nozzle, the housing, said conveyor tube and the second tubular element while a lower portion of said housing contains a body of the treating liquid in contiguous relation to the hollow member and at elevation below the outlet from said nozzle.

10. The combination as specified in claim 9, and an annular trough provided by said hollow member and disposed exteriorly of the remainder of said housing in which an end portion of said conveyor tube spaced from said second tubular element is situated in spaced relation to the hollow member.
